UNITED STATES PATENT OFFICE.

FRANK H. LANGMUIR, OF CHICAGO, ILLINOIS, ASSIGNOR TO ST. LOUIS TRUNK HARD-
WARE MFG. CO., OF ST. LOUIS, MISSOURI, A CORPORATION OF MISSOURI.

IRON HOLDER.

Application filed January 23, 1925. Serial No. 4,356.

To all whom it may concern:

Be it known that I, FRANK H. LANGMUIR, a citizen of Canada, residing at Chicago, Illinois, have invented a new and useful 5 Iron Holder, of which the following is a specification.

This invention relates to iron holders of a type specially, though not exclusively, designed and adapted for use in trunks and 10 the like.

An object of the invention is to provide an improved device for supporting and holding an iron within a trunk or the like so that the iron will be held stationary in the position 15 in which it is placed.

Another object of the invention is to provide an improved iron holder designed and adapted to be attached to a wall of a trunk or the like and comprising means for clamping the iron firmly in position, and constructed and arranged so that irons of various sizes may be mounted in the holder. 20

Another object of the invention is to provide an improved iron holder comprising a case for holding the iron spaced relatively a considerable distance from the wall to which the base is attached, and clamping means for securing the iron in connection with the base. 25

Various other objects will appear from the following description, reference being made to the drawing in which

Fig. 1 is an end elevation of my improved iron holder showing an iron in connection 30 therewith.

Fig. 2 is a front elevation of the iron holder.

Fig. 3 is a side elevation of the holder showing an iron thereon.

Fig. 4 is a rear elevation.

My improved iron holder comprises a base designed and adapted to be secured to a wall of a trunk or other support, and relatively movable supporting and clamping elements for engaging and holding an iron in connection with the base. As shown, the base comprises a plate shaped to provide flat side portions 1, a raised central portion 2 between and integrally united with the side portions 1, a raised flat portion 3 obtained by shaping the plate to provide the same, a U-shaped portion 4, one arm of which is integrally united with the parts 1 and 2 of the base and the other arm of which 45 is integrally united with extensions 5 in

the same plane with the portions 1, and bearing portions 6 which receive the in-turned ends 7 of the bail 8.

The bail constitutes one of the clamping or supporting elements cooperatively connected with the base. The other clamping or supporting element comprises a plate 9 60 slideable under the base plate in the channel provided between the parts 1 by the raised portion 2. The upper end of the plate 9 opposite the part 3 of the base is shaped to provide an outwardly extending portion 10 the edge of which is extended downwardly to provide a flange 11. An adjuster for the clamping device is provided comprising a rod 12 having a reduced threaded extension 13 passing through the portion 10 of the clamp and through both arms of the U-shaped portion 4 of the base. The shoulder on the stem at the beginning of the 65 threaded portion 13 abuts against the part 10 of the clamp, and a nut 14 is secured on the threaded portion 13 on the opposite side of the part 10 of the clamp. The nut 14 is secured in position so that it will not work 70 loose, but does not clamp against the part 10 leaving the stem free to turn. A nut 15 is secured on the stem between the arms of the U-shaped portion 4 of the base, so that when the stem is turned the clamping device will be moved to or from clamping 75 position as desired. The lower end of the stem has a washer 16 attached thereto to prevent separation of the parts. The upper end of the stem has a knurled knob 17 to 80 facilitate operation.

The manner of using the device will be readily understood by reference to the drawing in which it will be seen that the point of the iron is passed through the bail 8 and the bottom of the iron placed against the raised base portions 3 and 4. The flange 11 of the adjustable clamp is then pressed against the upper end of the iron by manipulation of the adjuster. The iron is thus 85 rigidly clamped and retained and may be conveniently carried in a trunk or mounted elsewhere as desired.

From the foregoing it is apparent that my invention obtains all of its intended objects and purposes in an efficient and economical manner. The raised portions of the base provide an air space between the iron and the wall to which the base is secured 90 so that the wall will not be burned or 105 110

scorched even though the iron be comparatively hot when mounted on the holder. It is obvious that the device may be varied in structural respects without departure 5 from the nature and principle of the invention.

I do not restrict myself unessentially, but what I claim and desire to secure by Letters Patent is:—

- 10 1. An iron holder comprising a base, a bail pivotally connected with the base to engage one end of an iron, and a clamp operatively connected with the base.
- 15 2. An iron holder comprising a base for connection with a support, a bail pivotally connected with the base to engage an iron, raised portions on the base for holding an iron spaced from the support, and a clamping device in connection with the base for 20 engaging an iron.
- 25 3. An iron holder having a base for connection with a support, raised portions on the base for holding an iron spaced from the support, a bail pivotally connected with the base for engaging one end of an iron, and a clamping device in connection with the base for engaging the opposite end of an iron.
- 30 4. An iron holder comprising a base, a bail pivotally connected with the base for engaging one end of an iron, a clamping device having slidable connection with the base, and an adjuster operatively connected with the base for adjusting said clamping device.
- 35

5. An iron holder comprising a base, a bail pivotally connected with the base, a clamp having slidable connection with the base, a rod extending through said clamp and through the base, and means for operating said clamp by said rod. 40

6. An iron holder having a base, a U-shaped portion in connection with the base, a clamp having slidable engagement with the base, a rod extending through said clamp and through said U-shaped portion of the base, and a nut screwed on said rod between the arms of said U-shaped portion of the base. 45

7. An iron holder having a base, a U-shaped portion in connection with the base, a clamp having slidable engagement with the base, a rod extending through said clamp and through said U-shaped portion of the base, a nut screwed on said rod between the arms of said U-shaped portion of the base, and means for moving said clamp to and from clamping position by said rod. 50 55

8. An iron holder having a base, a U-shaped portion in connection with the base, a clamp having slidable engagement with the base, a rod extending through said clamp and through said U-shaped portion of the base, a nut screwed on said rod between the arms of said U-shaped portion of the base, means for moving said clamp to and from clamping position by said rod, and means for preventing said rod from working out of connection with said parts. 60 65

FRANK H. LANGMUIR.
